UNITED STATES PATENT OFFICE

WILLIAM E. PELTON AND ERNEST H. HOLCOMBE, OF CANTON, PENNSYLVANIA

AX

Application filed January 25, 1932. Serial No. 588,698.

This invention relates to cutting tools of the ax or hatchet type.

An object of the invention is the provision of an ax or hatchet type of cutting tool having a cutting blade movable to an inoperative secured position within guard members forming extensions of a handle, the cutting blade being releasable from its locked position by means of a trigger conveniently mounted for actuation adjacent the handle.

Another object of the invention is the provision of an ax or hatchet type of tool having a movable cutting blade which may be positioned in an inoperative position between a pair of guard members or which may be released to a position which is substantially right angular to the longitudinal axis of the handle of the tool to form an ax or hatchet, the cutting blade being further releasable to a position where it is aligned longitudinally with the handle to provide in effect a chisel, the last-mentioned position of the cutting blade providing a tool which may be used for digging holes.

A further object of the invention is the provision of an ax or hatchet type of tool in which a cutting blade is movable to a plurality of positions and which may be locked in any of these positions and released by the pressure of a finger upon a spring-pressed trigger, only the finger-engaging portion of the trigger being exposed beyond a pair of guard members which normally house the cutting blade in an inoperative position.

This invention will be best understood from a consideration of the following detailed description, in view of the accompanying drawing forming a part of the specification; nevertheless, it is to be understood that the invention is not confined to the disclosure, being susceptible of such changes and modifications which shall define no material departure from the salient features of the invention as expressed in the appended claims.

In the drawing:

Figure 1 is a side view in elevation of an ax or hatchet type of tool,

Figure 2 is a transverse vertical section taken along the line 2—2 of Figure 1,

Figure 3 is a fragmentary view in perspective

of the trigger-operated keeper or locking device for the tool.

Figure 4 is a fragmentary side view in elevation of a modified form of the tool shown in Figure 1, and

Figure 5 is a fragmentary view in perspective of a trigger-actuated keeper or locking bar.

Referring more particularly to the drawing, 10 designates a handle formed of two similar sections 11 which are pressed or cast into a substantially semi-cylindrical form so that when the two sections are secured together by means of rivets or any other well known form of securing means, as indicated at 12, the handle will be substantially cylindrical and of a size which may be comfortably grasped by the hand. The outer end of the handle is knurled, as shown at 13, in order to prevent slippage when operating the tool.

A pair of guard members 14 are extended forwardly of the sections 11 of the handle 10 and are of such a size that they will completely house a cutting blade 15. The outer ends of the guard members 14 are curved, as shown at 16, and at approximately the center of the circle upon which the curve 16 is formed is mounted a pivot pin 17 for swingably supporting the cutting blade 15 while providing means for securing the outer ends of the guards in spaced relation.

The lower end of the guard members 14 are cut away, as shown at 18, in order to provide for the exposure of one side edge 19 of the blade 15 when the cutting blade has been completely housed between the spaced guard members 14 in order to permit the blade to be forced from the guard members in any approved manner if required. However, if the cutting blade and the guard members are kept in good condition the cutting blade will readily fall by gravity from the guard members to the position shown in Fig. 1 by the release of a locking bar or keeper, as will be presently explained.

The cutting blade 15 is provided with three notches 20, 21 and 22. The notches 20 and 21 are diametrically opposite each other while the notch 22 is approximately 90° from either the notch 20 or 21 or approximately midway

between the notches 20 and 21. It will be noted that the inner portion of the blade 15, as shown at 23, is rounded on a curve whose radius is less than the arc 16 so that the inner edge or wall of the notch 22 is of less height than the outer edge. This is also true of the side walls of the notch 20 since the curved portion of the inner end of the cutting tool, as shown at 24, is similar in construction to the curved portion 23.

A latch or locking bar 30 is pivotally mounted, at 31, on the upper adjacent portions of the guard members 14. This bar extends between the guard members along their upper edges, as shown at 32, and completely housed between the guard members so that the outer edge 33 of the latch bar is substantially flush with the outer edges 32 of the guard members 14. A pair of lugs 34 and 35 extend laterally from the outer free end of the latch bar 33 and an extension or lug 36 depends from the outer end of the latch bar in order to be received within the notch 22 of the cutting blade 15. The lugs 34 and 35 are received within notches 37 formed within the guard members 14. The cutting blade 15 is secured in place to provide a form of hatchet for the cutting tool.

The rear edges of the guard members 14 are slightly cut away, as shown at 40, in order to provide for the projection of a portion 41 of a trigger element 42, which is formed integrally with the keeper bar 30 and extends downwardly from the pivot point 31 of said keeper bar. The lower free end of the trigger is connected by a spring 43 with a pin 44 secured within the handle 10. The spring at all times tends to move the trigger rearwardly and thus maintains the keeper bar 30 in locking position within the notches 32 of the guard members 14 and one of the notches at the inner end of the cutting blade 15.

A hammer or head 45 is secured to the outer end of the keeper bar 33 and may be employed for driving nails.

The form shown in Figs. 4 and 5 is similar in construction to that shown in Figs. 1 to 3 with the exception of the construction 50 of the keeper bar 50. This bar it will be noted is of sufficient width to be located between the guard members 14 and is of sufficient length so that the lug 36 will be received within any one of the notches 20, 21 or 22 of the cutting tool 15. It will be noted, however, that the head 45 is absent as are the lugs 35 and 34 which in Fig. 1 are adapted to be received within notches 37 in the guard members 14.

60 The trigger 42 is pivoted at 31 on the guard members 14 and since the keeper bar 15 is formed integrally with the trigger 42, the keeper bar is pivotally mounted likewise at 31. The spring 43 maintains the trigger 65 and the keeper bar in a predetermined lock-

ing position. A portion 41 of the trigger 42 projects beyond the cut-out portions 40 of the guard members 14 so that the finger may engage the projection 41 and operate the trigger to release the keeper bar, as will be presently explained.

The operation of the device is as follows: When the tool is carried the cutting blade 15 is normally located within the guard members 14 so that the cutting edge 51 will be located adjacent the trigger 42. At this time the notch 21 will be engaged by the lug 36 of the keeper bar 33 so that the cutting blade will be held rigidly in position.

If it be desired to place the cutting blade 15 in the position shown in Fig. 1 so that the tool may be used as an ax or hatchet, the projecting portion 41 of the trigger 42 is pressed by the thumb whence the latch bar 31 will be moved outwardly from the guard members and thereby release the cutting blade 15 whence it will fall by gravity to the position shown in Fig. 1. As soon, however, that the blade has been released from its locked position within the housing the pressure on the portion 41 of the trigger 42 is removed so that when the blade moves to the position shown in Fig. 1, the notch 22 of said blade will receive the lug 36 while the lugs 34 and 35 will be received by the notches 37 of the guard members 14.

If it be desired to use the tool as a chisel, as a spade, or for any other purpose for which the tool may be adapted in this position, the trigger 42 is again actuated to release the keeper bar 30 so that the lugs 34, 35 and 36 will be removed from their respective notches, to permit freedom of movement of the cutting blade 15. A quick movement of the wrist when grasping the handle 10 will cause the cutting blade 15 to swing outwardly to a position which is in longitudinal alignment with the handle 10 until the lugs 34, 35 and 36 will again be received within their respective notches in the guard members 14 and the notch 20 in the cutting blade 15. In this position the tool may be used for many purposes.

When it is desired to return the cutting blade 15 to its position between the guard members 14 it is only necessary to again exert pressure on the trigger 42 whence the various lugs will be released from their respective notches so that the operator of the tool may swing the cutting blade 15 back to its normal inoperative position. At this time the notch 21 will receive the lug 36 while the lugs 34 and 35 will be received by the notches 37 of the guard member 14.

We claim:

In hatchet and ax type tools, a handle portion, a guard formed at one end of the handle and adapted to house a cutting blade, a cutting blade pivotally mounted at one end of the outer end of the guard, the end of the

cutting blade adjacent the pivoted portion being semi-circular and provided with peripheral notches formed in the opposite side edges of the blade and a peripheral notch intermediate the last-mentioned notches, a locking bar normally housed within the guard and having a lug at one end provided with an inner face and an outer face which has greater height than the inner face, the lug being adapted to engage any one of the notches for retaining the blade either in an inoperative position, in a position simulating an ax, or in a position simulating a chisel, one wall of two of the notches which is engaged by the inner face of the lug being of less height than the opposite wall, the peripheral edge of the inner end of the cutting blade being cut away on an arc of a curve adjacent the inner wall of two of the notches in the blade to provide for the complete housing of the locking bar when in locking position with the blade.
